UNITED STATES PATENT OFFICE.

EDWARD C. HOUGH, OF PLYMOUTH, MICHIGAN, ASSIGNOR TO DAISY MANUFACTURING COMPANY, OF PLYMOUTH, MICHIGAN, A CORPORATION OF MICHIGAN.

AIR-GUN.

No. 903,092.

Specification of Letters Patent.

Patented Nov. 3, 1908.

Application filed January 4, 1908. Serial No. 409,332.

To all whom it may concern:

Be it known that I, EDWARD C. HOUGH, a citizen of the United States of America, residing at Plymouth, in the county of Wayne and State of Michigan, have invented certain new and useful Improvements in Air-Guns, of which the following is a specification, reference being had therein to the accompanying drawings.

- 10 The invention relates to spring air guns formed with the usual true and false barrels arranged respectively one within and detachable from the other, and it consists primarily in novel means for locking the 15 barrel sections together; further, in means for holding the true barrel to its seat; and, still further, in certain details of construction as will be hereinafter set forth.
- 15 In the drawings illustrating my invention,—Figure 1 is a vertical longitudinal section through the false barrel of an air gun, showing the true barrel in elevation and the preferable locking and retaining means for the sections; Fig. 2 is a sectional 20 perspective view of the forward end of the gun; Fig. 3 is a similar view of the outer end of the false barrel; and Fig. 4 is a perspective view of the inner end of the true barrel.
- 25 In the drawings thus briefly described, the reference-letter A represents the usual false barrel of an air gun divided by a suitable apertured abutment or partition B into a magazine section C and an air compression 30 chamber D.

35 E represents the true barrel, carrying at its outer end the usual cap F adapted to fit within the false barrel, and at its inner end, with preferably a disk, or other suitable 40 guide, as F', for positioning the true barrel within the outer or false barrel to register properly with the opening leading to the compression chamber.

45 G designates the forward sight for the gun carried by and removable with the detachable true barrel and having a detachable locking engagement with the false. The sight, as shown, comprises a main section a, having a roughened or milled top 50 to permit of being actuated by the thumb of the operator, a shank section b, and a sleeve c loosely engaging the true barrel in proximity to the cap F.

55 H represents yielding means, preferably in the form of a spring coiled upon the true

barrel intermediate a suitable abutment d thereon, and the sleeve section c of the sight.

To permit of the detachable locking engagement between the sight and the false barrel, I provide the latter at its forward end with an opening e leading outwardly to the extreme end through a slot f which forms the inlet for the sight, and with a tongue g projecting within the opening in the forward portion thereof and in parallelism with the inlet f.

In assembling the parts, the true barrel is inserted within the false barrel, by a longitudinal sliding movement until properly seated at its rear end, when the cap F will 70 properly close the false barrel and the sight will be in the position indicated in dotted lines in Fig. 3. To lock the parts, the sight is moved rearwardly until it clears the projecting tongue g, then shifted laterally and 75 released, the spring acting automatically to throw the sight forwardly upon the side of the tongue g opposite the inlet.

In addition to automatically effecting the locking engagement between the true barrel 80 and the false barrel, the yielding means further serves to constantly hold the end of the inner barrel in contact with the abutment, so as to establish the proper communication between the parts. To remove the inner or 85 true barrel, the operation described is reversed, the sight being carried with the inner section.

What I claim as my invention is,—

1. In an air gun, the combination with a 90 false barrel, of a true barrel detachably arranged therein, and a relatively movable forward sight carried by the true barrel having a detachable interlocking engagement with the false barrel in the normal position of the 95 parts.

2. In an air gun, the combination with a false barrel, of a true barrel detachably arranged therein, and a relatively movable spring-pressed forward sight for the true 100 barrel having a locking engagement with the false barrel.

3. In an air gun, the combination with the false barrel, of a relatively movable forward sight therefor, a detachable true barrel 105 insertible within the false barrel by a longitudinal sliding movement, and yielding means intermediate the sight and true barrel acting to hold the latter to its seat.

4. In an air gun, the combination with a 110

false barrel, of a detachable true barrel slideable longitudinally within the false barrel, a relatively movable forward sight for the latter barrel carried by and removable with the true barrel, and yielding means between the sight and true barrel.

5. In an air gun, the combination with a false barrel, of the true barrel, a forward sight loosely sleeved upon the true barrel and having a detachable locking engagement with the false barrel, and a spring coiled upon the true barrel intermediate a bearing thereon and the sleeved sight.

6. In an air gun, the combination with a false barrel, of a true barrel detachably arranged therein, a forward sight for the former loosely sleeved on the latter adapted to lock said barrels in relation to each other, and yieldable means for holding the true barrel to its seat.
